[57] CLAIM

The ornamental design for a liquid dispenser, as shown and described.

DESCRIPTION

FIG. 1 is a top, front, and right side perspective view of a liquid dispenser showing my new design;
FIG. 2 is an enlarged front elevational view thereof;
FIG. 3 is an enlarged right side elevational view thereof, the left side being a mirror image of that shown;
FIG. 4 is an enlarged top plan view thereof;
FIG. 5 is an enlarged bottom plan view thereof;
FIG. 6 is an enlarged rear elevational view thereof;
FIG. 7 is a top, front, and right side perspective view of a second embodiment thereof, the only difference being the configuration of the actuator arm; and,
FIG. 8 is a top, front, and right side perspective view of a third embodiment thereto, the only difference being the configuration of the actuator arm.

FIG.1.

FIG. 2.

FIG. 3.

FIG. 4.

FIG. 5.

FIG. 6.

FIG. 7.

FIG. 8.
